**METHOD OF LAYING A PREFABRICATED
 ROADWAY**

Ludwig Wesch, Glucksburg-Ostsee, and Martin Ostermann, Hamburg-Hochkamp, Germany, assignors to Albert, Jean, Pierre CALS, Paris, France
 Filed Sept. 29, 1964, Ser. No. 400,100
 1 Claim. (Cl. 94—22)

The present invention relates to a prefabricated unit for the rapid assembly of reinforced surfaces, such as for roadways, airport runways, warehouse floors and so on, consisting of supporting beams for the application of covering plates thereon spaced from each other in parallel relation.

A method for the rapid production of roadways utilising a system of supporting beams, is already known. The girders crossing over the roads are secured on both sides of the road in side walls. The joists have in this case been spaced at 10 to 100 cm, preferably 20 cm. It has also been proposed to cover said supporting beam-framing, which consists mainly of concrete supporting beams, with resin fibre panels or similar plastic panels, the surface of which is provided with an artificial concrete layer.

The resin fibre panels of the prior art described above are glued to the beams. By the great flexible compliance of the resin fibre panels, it has been shown, that to lay the beams at distances, is very disadvantageous, since the resin fibre panels are easily bent with changes of load at points, and the glue area is extremely strained particularly on the edge of the beam. In time, a delamination of the resin fibre panel and a paring of the underlayer occurs. It would be possible to remove this disadvantage by considerably thickening the resin fibre panels, which for normal street traffic would have to be 10 to 20 mm. and more. However, it is not possible, even with panels with an increased thickness, to lay the joists spaced by more than 30 cm. It would be found, that the disadvantages of the hitherto known resin fibre panels are removed, if said latter are provided with a profiled reinforcement.

According to the invention, a prefabricated unit for the rapid construction of reinforced surfaces, such as roadways, airport runways, warehouse floors or the like, consists of supporting beams for the application of cover panels parallel spaced thereon, characterised in that the cover panels consist of at least one glass fibre reinforced plastic layer and an artificial concrete layer, and that additional strengthening beams, arranged transversely to the direction of the supporting beams between said latter and the cover panels, and preferably having an inversely hat-shaped cross-section are provided, grooves being arranged at intervals on the upper side of the supporting beam to receive said strengthening beams.

The strengthening beams may consist of glass fibre reinforced plastic materials, preferably polyester or epoxy resins or butadiene mixed polymer resins. If desired, the strengthening beams may alternatively be made from aluminum or steel.

The strengthening beams and the panels may be formed separately for use in the prefabricated units; however, the strengthening beams are advantageously rigidly connected to the cover panels by means of gluing and/or rivetting. This makes it possible to save one part of the construction on the site.

According to a preferred feature of the invention sections of pipe of appropriate length may be located in the inversely hat-sectioned strengthening beams, for the insertion of cables or supply conduits. This makes it possible to produce the necessary supply condits simulta-

2

neously without additional expense, during the laying of the prefabricated units. Also heaters or reinforcing means for cables, tubes or electric heaters, for example heating coils or heating wires, may be applied to the strengthening beams, which heaters may be subsequently constructed, if the strengthening beams are provided separately from the covering panels. The strengthening beams may be made of plastic material for insulating against damp or heat.

An incomplete prefabricated unit according to the invention, consisting only of covering panels and the hat-sectioned strengthening beams, can be used advantageously for the rapid construction of roadways or the like on a sandy or clay-type sub-soil. A method for the rapid construction of roadways or the like on sandy or clay-type subsoil with the use of an incomplete prefabricated unit of this type may comprise forming grooves corresponding to the strengthening beams in the subsoil, the strengthening beams connected previously with the covering panels being laid in said grooves, the subsoil being advantageously strengthened by means of an artificial resin, the covering panels and strengthening beams being laid before the artificial resin hardens.

In order that the invention may be more clearly understood, reference will now be made to the accompanying drawings, which show one embodiment thereof by way of example, in which:

FIGURE 1 is a view of a covering panel with inversely hat-shaped strengthening beams therebeneath, as viewed along the axis of said beams,

FIGURE 2 is a corresponding view of a support beam with grooves for the insertion of the strengthening beams shown in FIGURE 1,

FIGURE 3 is a view of the supporting beam of FIGURE 2 as viewed from above,

FIGURE 4 is a perspective view of a section of a laid surface made up of ready-made parts according to the invention with the cover partially broken away, and

FIGURE 5 is a fragmentary, exploded, perspective view, partly in section, showing a method for laying load-bearing, prefabricated assemblies on grooved, resin soaked soil.

Referring to the drawings, FIGURE 1 shows a cover panel 1 consisting of a glass fibre reinforced layer 2 and an artificial concrete layer 3 located thereon.

Strengthening beams 4 are arranged beneath the cover panels, the section of said beams preferably being inversely hat-shaped, as shown. One or more strengthening beams 4 of this type may be provided each according to requirements of use. These beams are made preferably from glass fibre reinforced plastics material, but other suitable materials are aluminum and steel.

FIGURE 2 shows a supporting beam 5 in a view corresponding to that of FIGURE 1. These supporting beams can for example be made of concrete. In the upper surface of the beam 5, grooves 6 are provided, which are formed to correspond to the section of the strengthening beams 4 and which are arranged at corresponding intervals from each other.

FIGURE 3 shows the same supporting beam 5 seen from above.

The strengthening beams 4 may be provided as separate parts of the ready-made unit, i.e. separated from the cover panels; however, in certain cases, it is preferred to fasten the beams 4 and the cover panels together in the factory, since this simplifies the assembly at the site.

The connection of the strengthening beams 4 with the cover panels 1 as well as the connection of both the strengthening beams and the cover panels 1 with the supporting beams 5, may be effected by gluing.

FIGURE 4 shows diagrammatically, in a perspective construction, a section of a reinforced surface constructed from prefabricated units according to the invention.

While the distance 7 between two adjacent supporting beams with a glass fibre reinforced covering panel 18 mm. thick, can amount to, at the most, 15-20 cm., it is possible with the prefabricated units according to the invention to increase said distance 7 from 30 cm. to 1 m. This distance is exclusively dependent upon the number of the strengthening beams per metre of the panel width, upon the moment of resistance of the cross-section profile and upon the bending strength of said strengthening beams.

The side supports for the supporting beams are shown as 8.

As materials for the strengthening beams 4, glass fibre reinforced plastics materials are preferred; however, iron and steel, as well as aluminium are also suitable. Strengthening beams 4 are variable sectional construction and/or variable material may be used over the breadth of the covering panel, or over the length of the supporting beam 5, the section of which material must be constructed to correspond to the groove spacing of the supporting beams. Within the inversely hat-shaped strengthening beams, pipes, heating elements, cables or also strengthening means may be located as necessary or desired.

Pipes built into the prefabricated units may be provided along the strengthening beams and may preferably be provided with fitting-means known per se, so that the fitting need only be effected at the side. In practice, the pipes are projected beyond the cover panels to be joined together with the strengthening beam, the fitting is placed ready on the extended cover panel and then the panels are slid over, whereby the tube within the strengthening beam does not take part in this movement of the covering panel, so that after the cover panel has been slid along, the tube projects beyond the other end of the strengthening beam, and consequently is ready again for producing the next fitting, if the tube is extended out of the strengthening beam sufficiently far from the next cover panel to be joined.

If the strengthening beams are supplied as separate parts of the units, then pipe-lines, cable-lines, heating devices or the like may be installed in the strengthening beams equipped with corresponding strengthening means, at the site before the cover panels are laid on the beams.

Finally, as shown in FIGURE 5, it may be an advantage to use incomplete prefabricated units according to the invention, i.e. without the supporting beams, if the units are to be used in sandy or clay-type ground for the rapid production of reinforced surfaces. It is sufficient to use cover panels 1 and strengthening beams 4, which are connected rigidly with the said latter, as construction units, grooves 12 corresponding to the profiles of the strengthening beams 4 being made in the ground before construction, and in which the prefabricated parts are laid. Advantageously the subsoil 14 may be strengthened by use of artificial resin with a basis of polyurethane or epoxy-polyamide resins and these resins may serve as adhesives if the prefabricated parts are laid before the resin hardens. The upper portion of the subsoil 14 is first soaked with an artificial resin, as shown at 16, for reinforcement, and the cover panels 1 are laid onto said grooves with the strengthening beams 4 disposed in the grooves 12 before said artificial resin hardens.

We claim:

A method for laying a prefabricated assembly for the rapid construction of roadways and other load-bearing surfaces on a sandy or clay-type soil, comprising the steps of providing cover panels having transverse strengthening beams on the undersurfaces thereof, forming grooves in said soil corresponding to said beams, soaking said soil with an artificial resin, laying said cover panels onto said soil with said beams being received in said grooves before said resin hardens, and allowing said resin to set.
